CLAIM

We claim the ornamental design for a rollable led light, as shown and described.

DESCRIPTION

FIG. 1 is a Perspective view of a rollable led light showing our new design in open position;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

The dash-dash broken lines in the drawings depict portions of the rollable led light that form no part of the claimed design. The hexagonal element in FIG. 5 shown in V-shaped broken lines also form no part of the claimed design.
